UNITED STATES PATENT OFFICE

2,509,165

SPECIAL USE ADAPTER FOR LIFTING JACKS

Virgil Pace, Hattiesburg, Miss., assignor to Pace
Tool Manufacturing Co., Inc., Hattiesburg,
Miss.

Application April 15, 1948, Serial No. 21,181

1 Claim. (Cl. 29—283)

1 By way of explanation, it might be stated that when repairing or overhauling the transmission or clutch of a motor vehicle, it is necessary to remove the differential of the vehicle to provide ample space and the necessary clearance between the forward end of the torque tube of a motor vehicle and the clutch or transmission of the vehicle, to accomplish the work.

It is therefore the primary object of the invention to provide an adapter for use in connection with the usual hydraulic jack, whereby the jack may be used in a horizontal position between the differential and an immovable or rigid element of the vehicle frame, to move the differential and torque tube rearwardly, providing ample space at the front end of the torque tube for a mechanic to repair the clutch or transmission, eliminating the necessity of removing the differential, thereby appreciably reducing the time and labor cost of repairing the clutch or transmission, to the minimum.

Another object of the invention is to provide an adapter of this character having means to permit of the ready mounting of the jack on the adapter for use in a horizontal plane, in such a way as to secure the jack in position on the adapter against accidental displacement when the jack is in operation to accomplish its purpose.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawing:

Figure 1 is a side elevational view illustrating the application of the adapter and jack positioned for use in moving the torque tube of the vehicle construction rearwardly.

Fig. 2 is a side elevational view illustrating the adapter and a hydraulic jack as removably connected therewith.

Fig. 3 is a plan view of the adapter.

Fig. 4 is a rear elevational view of the adapter illustrating the mounting tube of the adapter.

Referring to the drawing in detail, the adapter comprises the tubular body portion 5 to one end of which is secured the plate 6, the plate 6 being substantially wide and provided with outwardly and inwardly extended flanges 7 that are spaced from the main portion of the plate 6, as clearly shown by Fig. 3 of the drawing, providing a seat for the base 8 of the usual lifting jack 9, whereby the lifting jack may be readily and easily secured to the adapter so that the lifting jack may be

2 used in a horizontal plane to accomplish the purpose of the jack when used in moving the differential of a motor vehicle rearwardly disengaging the forward end thereof from associated mechanism.

At the opposite end of the body portion 5, is a relatively short mounting tube 10 which is so arranged that it may be fitted on the lowermost bolt of the torque housing, as shown by Fig. 1 of the drawing, thereby connecting this end of the adapter with the torque housing, so that when the jack is operated to move the differential housing rearwardly, accidental displacement of the adapter will be prevented.

From the foregoing it will be seen that when the device is positioned in a manner as illustrated by Fig. 1 of the drawing, and the bolts connecting the ball and socket mounting assembly of the torque tube, have been removed, operation of the jack to move the lifting bar of the jack outwardly, will tend to move the rear end or differential together with the torque tube, rearwardly, providing sufficient clearance at the front end of the torque tube to permit of ready access to the transmission or clutch, when it is desired to repair the transmission or clutch.

It is obvious that in the positioning of the adapter and jack to accomplish the purpose of the invention, the hook forming a part of the movable section of the usual jack, is positioned over the lower plate, connecting the members of the X frame of the vehicle, the X frame constituting the stationary or rigid section of the vehicle frame with which the jack and adapter are connected.

Having thus described my invention, what is claimed is:

An adapter bar for use with a lifting jack comprising an elongated body, a mounting tube secured to the side of the body with its outer end flush with the end of the body, said mounting tube adapted to be positioned over a bolt of a torque tube housing, a plate secured across the opposite end of the body, said plate being substantially wide, the side edges of the plate being extended forwardly and inwardly providing flanges between which the flanged base of a lifting jack, is held.

VIRGIL PACE.
